UNITED STATES PATENT OFFICE.

JOHN Q. SHERMAN, OF DAYTON, OHIO.

AUTOMATIC AUTOGRAPHIC REGISTER.

Application filed July 8, 1919. Serial No. 309,329.

My invention relates to autographic registers which have within or applied to them a source of power, such as a spring motor or other automatic driving means.

5 In devices of this character, the great difficulty involved in automatic operation is that a very definite amount of paper must be fed at each operation, and that duplicate strips must be fed equal distances,

10 without tearing or jamming. Thus positive stopping of the feed must be arranged for, and a simple method of releasing the feeding devices upon the application of power.

I have found it valuable in the construction of machines of the type described to provide for a tripping or releasing device which does not continue to release the feeding devices, so long as a single depression or throw of the latching elements is maintained by the operator, but merely releases them for one complete operation upon one throwing of the latches, so that all parts must return to normal prior to a second operation of the machine. This prevents 25 over-feeding, with its apparent disadvantages.

It is the object of my invention to provide in an autographic register for the features of advantage above noted, and generally to 30 provide a mechanism which will be durable, efficient and fool-proof.

I accomplish my objects and other advantages to be noted by that certain construction and arrangement of parts to be 35 hereinafter more specifically pointed out and claimed.

In the drawings.

The figure is a side elevation of one form 40 of autographic register embodying my invention.

While my invention is shown as applied to registers of the sprocket feed type, it should not be understood that this is the sole type of autographic register feeds to 45 which it is applicable. I have selected the sprocket feed type because it preserves registry of the strips of paper in a manner now well known in the art, and because in this type of feed the operating means must be more carefully regulated, stopped and started, in order to prevent any destruction of the great accuracy attained by the feeding devices, due to faulty operation.

I have shown the invention as applied to 55 an elementary and simple form of sprocket feed register, having no tension roll or tear-

ing blade. The invention could be applied to other types as well, such as, for example, to my register shown and described in Patent No. 1,259,918, of March 19, 1918, where-
in instead of an upper tension roll there is a spring-pressed tearing blade, as shown on sheet 1 of the drawings, or straight bar tearing blade, as shown on sheet 2 of the drawings.

In the device shown in the figure, the casing of the machine is shown at 1, and the lid at 2. The usual type of sprocket wheels are shown at 3, and strips of paper 4 are illustrated as being fed out of the machine in the usual manner by means of the sprockets.

Mounted on the side wall of the casing, in this instance on the outside of the casing, is a spring motor, having a spring 5, a ratchet and pawl 6 and 7 respectively, and a gear or pinion 8. This spring motor is thus of the same character as the usual clock spring, and in fact it is my desire to use a fairly large clock spring device for operating my register. No means for winding the spring is shown, as this will be of the usual clock spring type.

Located on the shaft 9 of the sprocket wheel is a pinion 10 which meshes with the gear 8 of the spring motor. This pinion has an arm 11 thereon which carries a contact pin 12. The arm 11 is adopted as a convenient means of applying a contact member to the pinion 10, and has no other function in particular. It is readily apparent that the spring motor will revolve the pinion 10 and through it the sprocket feeding devices.

Pivottally mounted at 13 on the side of the casing is a lever 14, which carries at its one end a stop pin 15, which moves into and out of the path of the contact pin 12 connected to the sprocket operating pinion 10. The lever is controlled at its other end by a spring 16, and its movement upward at this end is stopped by means of a stud 17, in the side of the casing. This stud is placed so that when the lever is free and under the influence of the spring, the stop pin 15 will be exactly in the path of the contact pin 12.

The tripping device for the lever comprises a plunger 18, sliding in a housing 19 on the side of the machine casing and controlled by a spring 20, which finds its lower bearing in any suitable fitting 21. The end 22 of the lever extends into the housing, and is there engaged by a pawl 23 carried by

the plunger and spring-pressed toward the lever end.

The conformation of the end of the lever and the pawl is such that when the plunger is depressed, the pawl operating against the end of the lever will depress it until the pawl rides past the nose 25 on its downward movement whereupon the spring 16 will return the lever 14 to its normal position.

10 When the plunger is released and rises, the pawl will be depressed by the nose 25, riding over this nose and will be returned to its position against the offset 24 by the spring 23 and the limit of its upward movement.

15 The lever 14 will thus operate to release the spring motor for operation at each depression of the plunger, and immediately assume a position which will positively stop the operation of the motor, by moving into 20 the path of the contact pin on the pinion 10. Thus the position of the lever being determined by its spring and the stop above noted, the sprockets will be permitted to revolve exactly one revolution at each depression of the plunger, and the fact that the operator maintains the plunger depressed 25 will have no effect on this operation.

It is also intended as above noted that the basic principle of my invention can be applied to other types of registers, and it is 30 believed that the above two examples will be sufficient to make clear the essential principles involved.

While a spring motor is shown, it is not 35 desired that I thereby be limited in the application of the points of advantage developed by my structure to spring motors alone, as some other form of power could be employed, with like results.

40 Having thus described my invention, what I claim as new and desire to secure by Letters Patent, is:

1. In an autographic register, the combination with a spring actuated member and 45 a paper feeding device, of means for operating the paper feeding device connected operatively to the spring actuated member, a release spring held in a normal feed stopping position to permit the spring member 50 to operate said feeding device through one complete movement only, and an operating device comprising a depressible member having means thereon to engage the release and trip it during a portion of its movement in one direction and free it during the 55 remainder of its motion in said direction, whereby sustained manipulation of said operating device will not result in continuous movement of the feeding device.

60 2. In a spring actuated autographic register, the combination with a spring actuated pinion adapted to operate the paper feeding element of the register, of a spring latch spring held in a normal feed stopping position adapted when tripped to permit one 65

complete movement only of the spring actuated pinion, and an operating device for said latch comprising a depressible member having means to engage and trip the latch during a portion of its movement in one direction and free the latch in the remainder of its motion in said direction, whereby a retaining of said tripping device out of normal position will not result in continued release of the latch.

75 3. A latch device for a power actuated autographic register, comprising a stop movable with the paper feeding mechanism of the register, and a movable spring stop normally in the path thereof, and a tripping device for the spring stop, adapted to move it out of the path of the first mentioned stop, and then release it, during each complete manual operation thereof thereby remaining out of engagement with said spring stop until returned to its normal position.

80 4. A latch device for a spring actuated autographic register, comprising a stop movable with the paper feeding mechanism of the register, and a movable spring stop normally in the path thereof, and a tripping device for the spring stop, comprising a depressible plunger and a dog thereon, said dog having a conformation to ride past the 85 spring stop, and said plunger being spring-pressed to carry the dog back to normal position ready for another operation.

85 5. In an autographic register, the combination with a feeding device adapted to feed strips of paper a definite amount for each 100 complete revolution of said rotary feeding device, of a pinion on said feeding device, a spring actuated gear in mesh with said pinion, a stop permanently located with regard to said pinion and movable therewith, and a spring latch normally in the path of said stop, and means to trip said latch out of said position.

105 6. In an autographic register, the combination with a feeding device adapted to feed strips of paper a definite amount for each 110 complete revolution of said rotary feeding device, of a pinion on said feeding device, a spring actuated gear in mesh with said pinion, a stop permanently located with regard to said pinion and movable therewith, and a spring latch normally in the path of said stop, and means to trip said latch out of 115 said position, said latch comprising a lever carrying a stop for lying in said path, a spring plunger on the register, a spring dog on the plunger, and faces on the dog and the lever arranged to contact as the plunger is depressed, said dog being mounted movably on the plunger and means preventing the 120 dog movement when in lever engagement on downward path of the plunger, the dog being free to move to pass the lever on its upward movement.

125 7. A latch for a spring actuated register,

comprising a lever, a spring for preserving said lever in latching position, a stop for the lever to definitely locate it in said latching position, a depressible carrier having a spring dog thereon, and said dog and lever arranged to contact as the carrier is depressed, said dog being mounted movably

on the carrier and means preventing the dog movement when in lever engagement on downward movement of the carrier, the dog ¹⁰ being free to pass the lever on its upward movement, thereby releasing said lever to permit it to return to latching position.

JOHN Q. SHERMAN.
